UNITED STATES PATENT OFFICE.

WILLIAM P. DENNIS, OF PHILADELPHIA, PENNSYLVANIA, ASSIGNOR TO WILLIAM EWERS,
OF PHILADELPHIA, PENNSYLVANIA.

DAMPER-REGULATOR.

No. 893,609.

Specification of Letters Patent.

Patented July 21, 1908.

Application filed August 30, 1907. Serial No. 390,705.

To all whom it may concern:

Be it known that I, WILLIAM P. DENNIS, a citizen of the United States, residing at Philadelphia, in the county of Philadelphia and 5 State of Pennsylvania, have invented certain new and useful Improvements in Damper-Regulators, of which the following is a specification.

This invention relates to improvements in 10 damper regulators and particularly to that class controlled directly or indirectly by the fluctuations of steam pressure in the boilers whose furnace stack draft is to be regulated.

The objects of the improvement are, first, 15 to provide an apparatus that shall be instantly responsive in action to a change in steam pressure in such boilers, in correcting either an excess or deficiency, if within its scope, thus maintaining uniformity of pressure. Second, to provide such devices as are not readily disarranged but durable and efficient in character and in which the operative parts are easily accessible without dismounting the entire mechanism. These and other 20 important objects are attained by the novel combination and arrangement of parts hereinafter fully described and shown in the accompanying drawings, forming part of these specifications, and in which have been used 25 similar characters of designation on all similar parts.

Figure 1, is a front elevation of the entire apparatus, including the pipe connections. Fig. 2, is a plan view of the same. Fig. 3, is 30 a front elevation of the controlling valve. Fig. 4, is a longitudinal section of Fig. 3 showing the controlling valve admitting fluid to operate the damper in one direction. Fig. 5, is a similar view showing the controlling 35 valve in an opposite position. Fig. 6, is a side elevation of the actuating mechanism, partially in section, showing the valve and piston construction. Fig. 7, is a partial front view of the piston valve stem attachment. Fig. 8, is a cross section of the controlling valve taken on line *a—a*, of Fig. 6. Fig. 9, is a cross section taken on line *b—b*, of Fig. 8. Fig. 10, is a detail of the piston valve. Fig. 11, is a cross section of the same, taken 40 on line *c—c*, of Fig. 10, and, Fig. 12, is a partial rear end view of the controlling valve.

The apparatus comprises a plate 1, adapted 45 to be secured by brackets—not shown—to a wall or other substantial support, conveniently located with reference to the

boiler and stack. On the upper face and near one end of the plate is a valve chamber 2, having the domed cover 3, and a diaphragm 4, secured between the flanges of the valve chamber and its cover, which are bolted as indicated. The space below the diaphragm 4, and also the connecting pipe A leading to the boilers, is filled with a liquid, as water, to about the height of the union A', so that the steam pressure of the boilers 50 may be directly exerted on the diaphragm when the valve A'', is open but the heat therein prevented from transmission to and hence injuring the material of which the diaphragm is made.

Passing through the top of the cover 3 and maintained vertically by a proper bearing formed therein, is the plunger 5, connected at the lower end to the diaphragm 4 and in such manner as to be operated by it. The 55 cover 3, has an integral upwardly projecting outer rib with an overhanging end 3', slotted to receive the end of the beam 6, in the recess thus formed and is provided with a seat in its lower edges for the angular knife-edge, 60 pivot bearing 6', set in the beam. This bar is further provided with another similar bearing 6'', attached to the beam in a reversed position, in register and to engage with the plunger 5, so that any lateral motion 65 thereof is communicated directly to the beam 6, held down by the pull of the weights 7, depending from the outer end of the said beam. A sliding counter weight 8, is 70 also adjustably connected to the beam, between the pendent weights and the beam guide 9. This latter comprises a standard, secured to the plate 1, having a slotted recess for the passage of the beam, and screws 75 9' and 9'', limiting the movement of the beam up and down respectively; a hand screw 10, set in a projection of the standard, provides means for locking the beam against 80 any movement if desirable.

The damper—not shown—is intended to 100 be connected with the end of the lever 11, pivotally supported by the fulcrum link 12, pivotally attached, at its upper end, to the lower side of the plate 1. The extreme end of the damper lever 11, is pivoted, at 13, to the lower end of the piston rod 14, passing upward through the stuffing box 15, and cylinder head 16, to the piston 17, within the cylinder 18, which is provided with a similar 105 head or cap 16'.

The piston head 17 is formed of two disks, both threaded to the rod 14, having clamped between them the cup leathers 17', placed reversely to each other and snugly fitting the bore of the cylinder. A lock nut 17", secures the disks in position in the usual manner; the nut also acting as a stop, limiting the movement of the piston in its upward stroke, contacting with the inwardly projecting hub of the cap 16'. At the other end of the stroke similar provision is made against excess movement by allowing the hub of the lower disk 17, to strike against the inner end of the stuffing box 15.

15 The cylinder 18, has an annular flange 18', midway of its length, adapted to be detachably secured to the plate 1; and it is further provided with ports 19 and 20, for the admission of the actuating medium either 20 above or below the piston 17, operating the same thereby.

Water, compressed-air, steam or other fluid under pressure is admitted from the pipe B, to the cylinder 18, through the valve 25 casing 21, by means of the piston valve 22, which passes upwardly through the stuffing box 23, and is attached at its upper end to a pivoted connecting member 24, having a means of adjustment at 25, and detachably 30 pivoted to the beam 6, but at one side thereof and not directly underneath, thereby affording means for conveniently disconnecting without disturbing the beam.

A single inlet 30, formed transversely to 35 the valve and two outlet passages 31 and 32, communicating directly with the ports 19 and 20, are formed respectively above and below the inlet 30 and in the same vertical plane but so that either or both may be 40 closed from communicating with it by the piston valve 22, which intersects with the ends of all these openings.

In one side of the body is formed a by-pass 33, having its upper terminus within the 45 bore of the valve 22, at right angles to the other passages and slightly above the upper outlet 31. Its lower end opens within the recess at the bottom of the valve body.

The piston valve 22, is of solid cylindrical 50 construction, having two reduced diametrical portions 31' and 32', providing a passage between the inlet 30 and outlets 31 and 32, as the valve is moved up or down. When the valve is raised a passage is opened between the inlet 30 and outlet 31, around the 55 reduced portion, admitting a current of fluid, while at the same time, the outlet 32 is open to exhaust from the cylinder through the bottom port of the valve body. When the 60 valve is down a similar passage-way is made between the inlet 30 and outlet 32, while exhaust from the cylinder takes place through the outlet 31, around the reduced area 31', to the by-pass 33, and then out at the bottom 65 of the valve body. If the valve be at a mid-

position obviously no passage of fluids can take place.

In the reduced portions of the valve I provide transverse holes 22' in order that the passage of fluids may be as free and unrestricted as possible and find the said holes result in a far more rapid and satisfactory action, besides which a more perfectly balanced valve is obtained.

The cylinder ports 19 and 20, are formed 75 in a projecting member 35, attached to the cylinder 18, and connected to the valve 21, by the coupling or lock nut 36; the face of the port containing member 35, is provided with depressions immediately surrounding the 80 port openings adapted to receive corresponding projections on the end of the valve body 21, the said projections entering into the depressions in the port member 35, and being maintained against rotary motion thereby, 85 as in connecting the valve body.

I have shown the connections as made with a right and left thread on the contacting members and a correspondingly threaded nut, but obviously I may use any form of a 90 union preferable.

In operation, steam from the boiler being connected to pipes A, water to pipe B, and the damper operatively attached to the lever 11, any excess of steam pressure in pipe A, 95 raises the diaphragm and hence the beam together with its weights and the valve 22; whereupon fluid from the pipe B, enters the valve body 21, passes through the lower passage past and partially through the opening 100 22', in the valve 22, and enters the cylinder 18 through the port 20, raising the valve 17, through its rod 14, operating the lever 11, in closing the damper and thus retarding the draft.

105 Obviously, the several weights on the beam may be adjusted to meet any steam pressure requirements desirable and when so adjusted will act operatively if their balance be overcome, as above described or reversely 110 upon occasion.

I am aware that devices for such purposes have long been in use, hence do not seek to cover the same broadly, but believe that devices possessing the peculiar characteristics 115 of my invention to be new,

Therefore having described the same, what I claim and desire to secure by Letters Patent is:

In a damper regulator, a supporting 120 bracket having mounted thereon a diaphragm chamber having connections leading to a boiler, a diaphragm contained therein and an upwardly projecting rod moved by said diaphragm, an arm pivoted and connected to the diaphragm rod to be moved thereby, said arm having at its upper end a suspended series of weights and a sliding weight, a supporting column attached to the other end of the bracket having a slot 125 130

through which the pivoted arm passes, and
adjustable screws forming stops for regulat-
ing the movement of said arm, a cylinder, a
piston therein and piston rod, said rod being
5 connected at its lower end to a lever pivoted
to the under side of the bracket and having
connections to a damper, a regulating valve
casing having two ports on one side con-
nected to opposite ends of the piston cham-
ber, and an inlet port located diametrically
10 opposite to the outlet ports but between the
same, the lower end of said valve casing be-
ing connected to an exhaust pipe, said casing
having a by-pass connecting its upper end
15 with the exhaust passage, and a piston valve
working in said valve casing, the upper end
of which is connected to the diaphragm op-
erated arm, said piston valve provided with
reduced areas so arranged that when the

valve is up, communication will be estab- 20
lished between the inlet port and one of the
outlet ports while the other port is open to
the exhaust, and that when said piston is
down the inlet port shall communicate with
the other or the lowermost outlet port while 25
the uppermost outlet port connects through
the by-pass with the exhaust, said piston at
its reduced portions having transverse pas-
sages through it for the passage of fluid from
the inlet to an outlet port. 30

In testimony whereof I have signed my
name to this specification in the presence of
two subscribing witnesses.
